UNITED STATES PATENT OFFICE.

JULIUS LAUFER, OF BERLIN, GERMANY, ASSIGNOR TO SIEMENS-SCHUCKERTWERKE,
G. M. B. H., OF SIEMENSSTADT, NEAR BERLIN, GERMANY, A CORPORATION OF
GERMANY.

INDUCTION-TRANSFORMER.

1,199,086.

Specification of Letters Patent. Patented Sept. 26, 1916.

Application filed April 24, 1914. Serial No. 834,112.

To all whom it may concern:

Be it known that I, JULIUS LAUFER, a German citizen, and resident of Berlin, Germany, have invented certain new and useful 5 Improvements in Induction-Transformers, of which the following is a specification.

My present invention relates to induction 10 transformers, that is to transformers of the induction motor type, which consist of a fixed member or stator and a rotary member 15 or rotor, and which are adjusted by the relative position of the stator and rotor for changing the relative phase values of the stator and rotor current, whereby phase-displaced currents may be generated, for instance for improving the power factor of 20 an alternating current line.

In order to maintain the adjustment of 25 the rotor which is ordinarily accomplished by means of a hand wheel, the rotary axle or said hand wheel mechanism must be locked against undesired rotations. This, however, results into the disadvantage that an exceedingly large rush of current will be 30 caused, for instance by a short-circuit of one of the members of the induction transformer. This rush of current is furthermore fully brought to action by reason of the small reactance of the induction 35 transformer. Upon the rotor of the transformer therefore an exceedingly large torque will be exerted so that the apparatus will have the tendency to act as an induction motor and to rotate with great force, which may 40 cause either the rotor body to become loose, or a distortion or breaking of the rather long and thin rotor axle or other injuries to the adjusting mechanism for the rotor.

The object of my invention consists in 45 providing means for protecting an induction transformer against such injuries in that free rotation of the rotor will be enabled in case a certain limit of torque is surpassed. For this purpose the rotor is 50 coupled with the adjusting mechanism, for instance by means of a slip coupling, which is so adjusted that the friction between the two halves of the coupling will be overcome in case of a torque which is exceeding a permissible value. As regards the location of 55 the coupling between the rotor body and the locking or adjusting means it is unessential whether for instance the coupling is arranged between the rotor axle and the axle

of the adjusting mechanism, or whether the 55 rotor body is constructed to be rotatable upon the axle and a yielding coupling provided therebetween. The construction may be also made in such a manner that the coupling will be disengaged in case of the torque 60 assuming an impermissible value. This disengaging is preferably accomplished electrically in dependence from the rotor current, and if the rotor body will be loosely mounted on the axle, this disengaging may be 65 done by means of bolts which are electro-magnetically actuated from the rotor windings, said bolts being normally in engagement with the axle and coming out of engagement in case of a rush of current. 70

In the accompanying drawing I have shown an example of a construction according to my present invention.

Figure 1 is an elevation of an induction 75 transformer comprising a slip-coupling according to my present invention, Fig. 2 shows a modified device for uncoupling the rotor from its axle by means of shear bolts and Fig. 3 represents a similar device for electro-magnetically disengaging the rotor. 80

a is the stator of the induction transformer, *b* the rotor of the same, *c* the slip rings, *d* the axle which is carried through the bearing *e* mounted at the upper and a similar bearing at the lower end of the 85 stator. The afore-mentioned slip-coupling is indicated at *g*. The adjusting device for adjusting the rotor in different angular positions is indicated by a worm gear *h*, *i*, which may be operated by a crank or hand 90 wheel or in any other desired manner. In Fig. 2 the coupling device which may be substituted for the slip-coupling, comprises essentially a bolt *j* which is passed through a bore-hole in the hub of the rotor body *b* 95 and the axle *d*, said bolt *j* being so dimensioned that it will be shorn off at a definite torque between the axle *d* and the rotor body *b*; thus permitting free rotation of the rotor body. The electro-magnetic means for disengaging the coupling between the rotor and its axle, as shown in Fig. 3 consist of a pin or bolt *k* passing through a hole in the hub of the rotor and normally engaging the same with its axle, which pin or bolt is 100 drawn out by the solenoid *l* which may be connected to the rotor windings. 105

Having thus described my invention I

claim as new and desire to secure by Letters Patent of the United States:—

1. In an induction transformer the combination of a stator and a rotor, an adjusting mechanism for adjusting the position of said rotor relatively to said stator, and coupling means intermediate between said adjusting mechanism and said rotor, said coupling means being adapted to mechanically disengage said rotor from said adjusting mechanism, if the torque exerted by said rotor surpasses a certain maximum value.
2. In an induction transformer the com-

bination of a stator and a rotor, an adjusting mechanism for adjusting the position of said rotor, and a slip-coupling adapted to disengage said rotor from said adjusting mechanism, if the torque exerted by said rotor surpasses a certain maximum value. 15

In witness whereof I have hereunto set my 20 signature in the presence of two subscribing witnesses.

JULIUS LAUFER.
